UNITED STATES PATENT OFFICE

EMIL R. KLEMM, JR., OF CHICAGO, ILLINOIS

TAPPET

Application filed September 10, 1928. Serial No. 305,069.

My invention relates to improvements in tappets and more particularly it relates to tappets which are operable to actuate a valve or other reciprocally movable element with which the tappet has end contact. A well known use for such tappets is that of functioning as a push rod for a valve seated immediately above the tappet and in vertical alignment therewith although such tappets 10 may be used in other capacities and positions.

A cam which is operatively connected with the lower end of the tappet imparts longitudinal movement thereto and brings the tappet into end contact with the stem of the 15 valve, momentarily unseating the valve. The upper end of the tappet projects from a guide in which it is mounted and longitudinally movable. The upper projecting end of the tappet is preferably spaced from one thirty- 20 second to one sixty-fourth of an inch away from the adjacent end of the valve stem, such spacing being called "valve clearance" or "air gap" by those versed in the art. The abrasion resulting from contact of the tappet with the 25 lower end of the valve stem and with the cam in time shortens the tappet sufficiently that the valve clearance or air gap exceeds one thirty-second of an inch, which is the maximum space at which the tappet functions 30 properly. If the air gap exceeds one thirty-second of an inch the valve will close too early and open too late, resulting in uneven running and general lowering of efficiency, accompanied by undesirable noises or knocking of 35 the parts.

When the air gap for any reason exceeds the maximum allowable of one thirty-second of an inch satisfactory operation requires either that the parts be lengthened or replaced. Replacement of the tappet at such 40 frequent intervals as is required for normal use is undesirable because of the time required and the expense incidental thereto. Any provision for lengthening the tappet 45 which requires for its accomplishment that it be removed from its mounting is undesirable for the same reasons. I am aware that many types of tappets are constructed and mounted in such a way as to be adjustable to compensate for shortening occasioned by use 50

without removing the tappets from their mountings. Such adjustments usually take the form of a lock nut and screw or other similar device, and all such devices require that the adjusting end project from the tappet guide a considerable amount. For tappets whose maximum projection above their 55 guide is one-quarter to three-eighths of an inch, as is the case with the engine of the Ford car, there is insufficient room for adjustment of this character.

The Ford tappet is constructed with no provision for adjustment, and the instruction charts descriptive of such tappets frequently contains the statement that "when the push rods (tappets) become worn it is best to replace with new ones." Because of the loss of time and the expense incident to replacement of such tappets, they are in practice frequently continued in use 60 when worn beyond the proper valve clearance or air gap space, with the resulting knocking noise and loss of efficiency, and it is the primary object of the invention to provide a tappet or push rod which is adjustable without removal from its mounting to compensate for shortening due to abrasion and which is adapted for use with a Ford engine or other engines having tappets which project only slightly from the guide in which it is mounted.

An object is the provision of means whereby the valve clearance of engines of the class described may be easily adjusted and maintained substantially constant over a long period of use.

Still another object is the provision of means whereby the period of usefulness of tappets of the class described may be increased.

Many other objects and advantages of the 85 construction herein shown and described will be obvious to those skilled in the art from the disclosure herein given.

To this end my invention consists in the novel construction, arrangement and combination of parts herein shown and described, and more particularly pointed out in the 90 claims.

In the drawings, wherein like reference characters indicate like or corresponding 100 parts:

Fig. 1 is a sectional view through a tappet equipped with one form of the device of my invention;

Fig. 2 is a plan view of the tappet shown in Fig. 1;

Fig. 3 is a sectional view along the line 3—3 of Fig. 1;

Fig. 4 is a sectional view of another embodiment of the invention;

Fig. 5 is a sectional view of still another embodiment of the invention; and

Fig. 6 is a perspective view of open end of the main body portion of the tappet.

Referring now to the drawings, wherein I have illustrated several embodiments of my invention, the numeral 10 designates a tappet mounted in a guide 11. The guide 11 is a portion of an engine of an automobile or the like in which the tappet is longitudinally movable. The lower end of the tappet is provided with an expanded portion 12 with which a cam 13 operatively engages to impart longitudinal motion to the tappet. The upper end of the tappet 10 is shown as spaced slightly away from a valve stem 14, this space being called the "air gap" or "valve clearance". Rotation of the cam 13 brings the end of the tappet into contact with the stem 14 and moves the stem 14 vertically thereby unseating the valve (not shown). It is obvious that continued operation of the parts will result in abrasion and a resultant shortening of the tappet 10. This shortening will increase the air gap or valve clearance between the end of the tappet and the end of the stem 14. The distance from the top of the guide 11 to the end of the tappet being limited to three-eighths of an inch and for the purpose of providing longitudinal adjustment of the tappet 10 in such limited space, I have provided a cap 15 which has a stem 16 projecting downwardly through a bore 17 in the main body portion of the tappet. The cap 15 is low and utilizes only a portion of the limited projecting end of the tappet of which it forms a part. The lower edge of the cap 15 is provided with a plurality of serrations 18 which fit corresponding serrations 18 on the main body of the tappet. The serrations 18 are relatively small, and are correspondingly stepped upwardly on opposite sides, the difference in elevation of adjacent serrations being preferably not more than one sixty-fourth of an inch. The general direction of the opposite semi-circumferential edges is that of similarly sloping spirals and the serrations take a generally radial direction. A socket 20 in the wall of the guide 11 provides access to a cup screw 21 which is normally threaded into engagement with the stem 16 to hold the cap 15 against movement relative to the main body of the stem. When the tappet needs adjustment, the screw 21 is loosened by means of a

wrench inserted in the socket 20. The cap 15 is then lifted and turned in an anti-clockwise direction, the width of one serration or if the abrasion of the parts has been excessive the shift may be made through two or more serrations. The screw 21 is then tightened and the cap thereby held in adjusted position against possibility of movement until further adjustment becomes necessary when the operation can be repeated. This adjusting operation may be repeated until the cap has been rotated through substantially one-fourth a circumference.

An alternative form of my invention is disclosed in Fig. 4 where the main body portion of the tappet 22 is provided with a cap 23, the tappet and cap being connected by means of a plurality of serrations 18 similarly arranged and positioned as in Fig. 1. The cap 23 is held in seated position by a tensile spiral spring 24 which is mounted in a bore 35 formed in the body of the tappet. The spring 24 is fastened at its upper end to a boss 37 which forms part of a stem 36 extending downwardly from the cap 23. At the lower end the spring 24 is connected with a rivet or pin 25.

The spring 24 is so formed that adjustment of the cap 23, by turning in anti-clockwise direction, increases the resistance of the spring. The spring 24 permits the cap 23 to be lifted and turned sufficiently to accomplish the required adjustment and then functions to hold the cap securely in place.

In Fig. 5 I have shown still another embodiment of my invention, in which the tappet 30 takes the same general form as that of the tappet 10. The main body portion of this tappet 30 contains a relatively large bore 38 into which a member 39 having a cap 31 is threaded. A stem 32 projects downwardly from the member 39 into the small bore 33. The cap 31 and member 39 are held firmly in adjusted position by a cup screw 34 which is similar in construction and operation to the screw 21. The length of the tappet 30 is changed by loosening the screw 34 and threading the member 39 in the desired direction. A thin, flat wrench capable of insertion in a limited space may be used for this purpose.

Each of the caps 15, 23, and 31 are recessed to receive a tight fitting washer or disk 40. The disk 40 is constructed of tough non-metallic material which serves as a cushion and minimizes the noise that would otherwise result from the impact of the tappet with the valve stem 14.

Having thus described my invention, it is obvious that various immaterial modifications may be made in the same without departing from the spirit of my invention; hence I do not wish to be understood as limiting myself to the exact form, construction,

arrangement and combination of parts herein shown and described or uses mentioned.

What I claim as new and desire to secure by Letters Patent is:

5. A tappet comprising a cylindrical shaped main member open at one end and a relatively shallow cap member seated on the open end of the main member for the purpose described, one semi-circumferential segment 10 of the open end face of the main member being serrated and inclined to form a spiral and the other segment of the end face being similarly serrated and spiralled, said cap member being serrated and spiralled to fit the 15 open end of the main member and means adapted to hold the cap member seated on the main member. 70
6. A tappet comprising a cylindrical main member open at one end, a relatively shallow cap member seated on the open end of the main member for the purpose described, and means adapted to hold the cap member seated on the main member, one semicircumferential segment of the open end face of the main 25 member being inclined to form a spiral and having a plurality of similar radially extending serrations formed therein and the opposite semi-circumferential segment of said face being similarly serrated and spiralled. 80
7. A tappet, a guide in which the tappet is longitudinally movable, a cam operatively connected with one end of the tappet, the other end of the tappet projecting slightly from the guide, the tappet comprising a cylindrical main member open at said projecting end and a relatively shallow cap member seated on the open end of the main member for the purpose described, one semi-circumferential segment of the open end face of the main member being serrated and inclined to form a spiral and the other segment of the end face being similarly serrated and spiralled to fit the open end of the main member, and means adapted to hold the cap member seated on the main member. 85
8. A tappet, a guide in which the tappet is longitudinally movable, a cam operatively connected with one end of the tappet, the other end of the tappet projecting slightly 90 from the guide, the tappet comprising a cylindrical main member open at said projecting end, one semi-circumferential segment of the open end face of the main member being inclined to form a spiral and having a plurality of similar radially extending serrations formed therein and the opposite semi-circumferential segment of said face being similarly serrated and spiralled, said cap member being oppositely spiralled and serrated similarly to said main member whereby the cap member can be seated in a plurality 95 of positions on said main member. 90
9. A tappet comprising a cylindrical shaped main member open at one end and a relatively shallow cap member seated on the open end of the main body portion for the purpose described, one semi-circumferential segment of the end face of the main member 100 being serrated and inclined to form a spiral and the other segment of the end face being similarly serrated and spiralled, said cap member being serrated and spiralled to fit the open end of the main member and means adapted to hold the cap member seated on the main member, said means comprising a stem projecting from the cap member into the main member and a screw mounted in the wall of said main member and operable to engage 105 said stem. 100
10. A tappet comprising a cylindrical main member open at one end, a relatively shallow cap member seated on the open end of the main member for the purpose described and means adapted to hold the cap member seated on the main member comprising a stem projecting from the cap member into said cylindrical member and a screw mounted in the wall of said main member in operative engagement with the stem, one semi-circumferential segment of the open end face main member being inclined to form a spiral and having a plurality of similar radially extending serrations formed therein and the opposite semi-circumferential segment of said 110 main member being serrated and inclined to form a spiral, and the other segment of the end face being 115
11. A tappet comprising a cylindrically shaped main member open at one end and a relatively shallow cap member seated on the open end of the main member for the purpose described, one semi-circumferential segment of the open end face of the main member being serrated and inclined to form a spiral, and the other segment of the end face being 120
12. A tappet comprising a cylindrically shaped main member open at one end and a relatively shallow cap member seated on the open end of the main member for the purpose described, one semi-circumferential segment of the open end face of the main member being serrated and inclined to form a spiral, and the other segment of the end face being 125

similarly serrated and spiralled, said cap member being serrated and spiralled to fit the open end of the main member, said co-operating serrated ends comprising alternate inclined and longitudinally extending faces permitting rotation of the cap member in sliding contact with the main member in only one direction, and means adapted to hold the cap member seated on the main member.

10 In testimony whereof, I have hereunto signed my name.
